UNITED STATES PATENT OFFICE.

CHARLES S. ASH, OF HAGERSTOWN, MARYLAND.

QUICK-DETACHABLE VEHICLE WHEEL.

Application filed August 6, 1919. Serial No. 315,589.

To all whom it may concern:

Be it known that I, CHARLES S. ASH, a citizen of the United States, residing at Hagerstown, in the county of Washington 5 and State of Maryland, have invented certain new and useful Improvements in Quick-Detachable Vehicle Wheels, of which the following is a full, clear, and exact description, such as will enable others skilled in 10 the art to which it appertains to make and use the same.

This invention relates to quick detachable vehicle wheels, and more particularly to an improved construction of hub for wire 15 spoked wheels.

It is an object of the invention to provide a wheel hub of the character mentioned which is capable of economical and expeditious manufacture, which is strong and 20 efficient in service, and which is of improved appearance.

A further object is to provide an outer hub for wire spoked wheels which is structurally superior and functionally advanced. 25

The accompanying drawing illustrates a typical preferred embodiment of the invention and shows, in

Figure 1, an end elevation of the improved 30 hub;

Fig. 2, a central longitudinal section thereof; and

Fig. 3, a detailed section on the line B—B of Fig. 1.

Referring more particularly to the drawing, there is shown a hub of pressed steel 35 comprising an enlarged flange 1 at its inner end, a smaller flange 2 at its outer end, and an intermediate body 3. In manufacture, a plurality (in the present instance six) of 40 axially disposed, open bosses or sockets 4 are punched from the body 3 adjacent the inner spoke flange 1. The bosses 4 are at equal distances radially of the center of the hub 45 and are symmetrically spaced circumferentially. These bosses are open at both ends and are adapted to receive the extremities of corresponding driving lugs on the inner hub when the wheel is mounted.

To facilitate the mounting of the wheel, 50 there are provided two metal fillers 5 radially opposite and positioned between adjacent bosses 4. The fillers 5 are preferably curved concentrically of the hub and are 55 of a dimension so that their surface lies flush

with the inner ends of the bosses. In mounting the wheel, consequently, if the hub does not occupy a relative rotary position to receive the driving pins, certain of the latter will abut the fillers 5, whereupon the outer 60 hub may be readily rotated while pushed inward until the open bosses register with the driving pins.

In order to seal the openings through bosses 4, there is provided a thin metal ring 65 or annulus 6 having a central opening such that the ring may be fitted past the hub flange 2 and the inner edge of the ring forced or sprung on the body 3, where the latter is fed inward at 7. The ring 6 is sufficiently 70 wide so that its outer edge overlaps somewhat the outer surface of the hub flange 1, and the ring is shaped to afford a smooth substantially continuous wall with the adjacent walls of the hub. In practice, the ring 75 6 may have a driving fit with the hub shell at 7, or may be secured to the shell, as by welding along the overlapping edge 8.

The construction of the hub as described is particularly advantageous in that the cost 80 of manufacture thereof is kept at a minimum, while, on account of the material used and the construction, adequate strength is insured to resist the driving shocks encountered in service. The bosses 4 open at 85 both ends are thus adapted to receive the driving pins and allow the hub to be pressed snugly home, so that the fixed ends of said pins are closely encircled by the walls of bosses 4. At the same time the hub is sealed 90 against the entry of foreign matter through the openings and presents an exteriorly imperforate appearance.

Having described my invention, what I claim as new and desire to secure by Letters 95 Patent, is:—

In a quick detachable vehicle wheel hub, in combination, a pressed metal shell having an enlarged spoke flange at one end and having adjacent axially open bosses struck inward from the body of the shell, and means between certain of said bosses substantially flush with the ends thereof, for the purpose set forth.

In testimony whereof I affix my signature, 105 in the presence of two witnesses.

CHARLES S. ASH.
